UNITED STATES PATENT OFFICE.

ERNEST GODDARD, OF BOISE, IDAHO.

TOILET-COVER.

No. 909,885.

Specification of Letters Patent. Patented Jan. 19, 1909.

Application filed January 23, 1907. Serial No. 353,752.

To all whom it may concern:

Be it known that I, ERNEST GODDARD, a citizen of the United States, residing at Boise, in the county of Ada and State of Idaho, 5 have invented new and useful Improvements in Toilet-Covers, of which the following is a specification.

This invention relates to protecting coverings or shields designed for use in connection with latrine bowl seats, and has for its objects to provide a simple, inexpensive device of this nature which may be conveniently transported and readily applied for use, one whereby the desired sanitation and protection against uncleanly conditions will be effectually attained, and one which in practice will completely cover the seat for preserving the occupant thereof wholly from direct contact therewith, thus to insure 20 against disease contagion.

With these and other objects in view, the invention comprises the novel features of construction and combination of parts more fully hereinafter described and particularly 25 pointed out in the claim.

In the accompanying drawing: The figure of the drawing is a top plan view of my improved shield.

Applicable to a seat of a latrine bowl is a 30 protecting covering or shield 5, composed of paper, sheet rubber or other desired appropriate material, and having an opening 6 designed to register with the opening of the seat, the covering being made of elliptical 35 form, as shown, or of other suitable shape to accord with that of the seat, while formed on the covering at the forward end of the opening 6 and to project into the latter is a guard extension or tab 7, the function of 40 which will presently appear.

The covering 5 which may be stamped or otherwise formed from a sheet or blank of material is of greater dimensions than those of the seat of the latrine bowl, while the 45 opening 6, which is of smaller dimensions than those of the opening of the seat, is formed eccentrically in the covering, whereby that portion of the latter bounding the front of the opening is of greater area than that of 50 the portion of the covering which bounds the rear of the opening, this difference in extent of the surface area of said portions being denoted by the dotted line 8 in the figure of the drawing.

55 In practice, the shield 5 is arranged in position on a seat with the outer marginal

edge of the covering turned downward around the outer edge of the seat and the inner marginal edge of the covering similarly turned around the marginal edge of the seat opening, the portion of the covering lying in advance of the line 8 being turned downward at the front of the seat in the form of an apron 9 while the guard piece 7 is arranged to project downward into the bowl at the 60 forward end of the seat opening 3. It is apparent that when the covering shield is applied as explained, the seat will be completely covered for protecting the occupant against uncleanly and unsanitary conditions, 65 while the apron 9 and guard 7 will obviate contact of any part of the occupant's person with the seat or bowl, thus amply insuring against disease contagion. By employing sheet rubber, water proof paper or analogous 70 pliable material in the production of the covering, the latter may be rolled or folded for convenient transportation and may be readily cleaned from time to time as desired, or discarded after use, it being understood, however, that the shield may be formed from celluloid or other desired appropriate 75 material.

The marginal edge of the covering surrounding the opening 6 is notched or gored 80 at suitably spaced intervals, as at 10, to insure convenient folding of the covering around the edge of the seat opening, the gores 10 being closed by webs 11 of a thinner, more pliable material than that of which the covering is composed, while formed in the guard 85 extension 7 is a gore 12, closed by a web 13, it being understood, however, that in this instance the shield may be stamped or otherwise formed with the marginal edge intact 90 or merely slit at two or more points to facilitate folding.

I wish it to be understood that the V-shaped notched portions with the webbed reinforcements attached to the marginal cuts of the opening and the cut of the apron prevent tearing or puckering when pressure is brought to bear on the same when in use, and further said web reinforces serve to keep the device 95 in proper shape.

Having thus described my invention, what I claim is:

A covering for latrine bowl seats comprising a sheet of suitable material having an aperture therein provided with a series of 100 V-shaped gores cut from its marginal edge and extending nearly around the same and hav-

ing webbed reinforcements secured thereto, an enlarged guard also cut from the front of the sheet and extending inwardly towards the opening, and provided with a V-shaped 5 gore having a webbed reinforcement secured thereto, said sheet also having an apron on its front portion, and said reinforcements of said marginal gores and said guard serving

to prevent puckering or tearing of the same, substantially as specified.

In testimony whereof, I affix my signature in presence of two witnesses.
